UNITED STATES PATENT OFFICE.

RICHARD T. NEWTON, OF NEW YORK, N. Y.

DESIGN FOR A BUMPER-BAR.

57,712.

Specification for Design.

Patented Apr. 26, 1921.

Application filed January 24, 1921. Serial No. 439,700. Term of patent 14 years.

To all whom it may concern:

Be it known that I, RICHARD T. NEWTON, a citizen of the United States of America, residing at New York city, in the county of New York, and State of New York, have invented a new and original Design for a Bumper-Bar, of which the following is a specification, reference being had to the accompanying drawing, forming part thereof.

Figure 1 is a plan view of a bumper showing my new design; and Fig. 2 is a front elevation thereof.

I claim:

The ornamental design for a bumper bar, as shown.

RICHARD T. NEWTON.

Witness:

E. M. LOCKWOOD.
